[57] CLAIM

The ornamental design for a remote control, as shown and described.

DESCRIPTION

FIG. 1 is a perspective view of a remote control showing my new design;

FIG. 2 is a top plan view thereof;

FIG. 3 is an bottom plan view thereof;

FIG. 4 is a front elevational view thereof;

FIG. 5 is a rear elevational view thereof; and,

FIG. 6 is a right side elevational view with the left side being a mirror image thereof.

The indicia and buttons in FIGS. 1 and 6 and the battery compartment in FIG. 3 are shown in broken lines for illustrative purposes only and form no part of the claimed design.
